REFRIGERATED UPRIGHT DISPLAY CASE

Donald A. Musgrave and James M. Bell, Conway, Ark., assignors to UMC Industries, Inc., New York, N.Y.

Filed July 28, 1972, Ser. No. 276,138

Term of patent 14 years

Int. Cl. D20—02

U.S. Cl. D6—187

FIG. 1.

FIG. 2.

FIG. 3.

FIG. 4.

FIG. 5.

FIG. 6.

FIG. 7.

FIG. 1 provides a perspective view of a refrigerated upright display case embodying our new design;

FIG. 2 is a front view of the display case;

FIG. 3 provides a left side view of the display case, the right side view being a mirror image in appearance;

FIG. 4 provides a top view of the display case;

FIG. 5 provides a bottom view of the display case;

FIG. 6 provides a perspective view of a modified, two door version, of the refrigerated upright display case shown in FIG. 1; and

FIG. 7 is a view in front elevation of the display case shown in FIG. 6.

The back of the display case is conventional in configuration.

We claim:

The ornamental design for a refrigerated upright display case, as shown and described.
